UNITED STATES PATENT OFFICE

PAUL AUGNER, OF PHILADELPHIA, PENNSYLVANIA

PROPELLER

Application filed December 3, 1931. Serial No. 578,706.

My invention relates to new and useful improvements in a propeller and while the illustration and description will relate its use in connection with a ship that travels in water, 5 I do not intend to limit the use of such propeller since it may be applied to airships.

One of the objects of my invention is to provide a system of propelling ships which consists in utilizing the swirling currents of 10 fluid, either water or air, discharged by the primary propeller against a secondary propeller and then transferring the power created by the secondary propeller back to the primary propeller in order to create more 15 power than generated by the prime mover in order to revolve the primary propeller at greater speed or at a predetermined speed with less power from the prime mover so as to bring about a saving in fuel.

20 Another object of the invention is to provide a secondary propeller in combination with a primary propeller with means for transmitting motion from the secondary propeller to the primary one.

25 Another object of the invention is to provide two propellers in endwise alignment, one of which is mounted upon a shaft to revolve therewith and the other journaled to revolve said shaft and receiving its power from currents of fluid produced by the primary propeller and a train of gearing so arranged that the power developed by the secondary propeller will be transferred to the shaft and thence to the primary propeller.

30 A further object of the invention is to provide a system of propelling ships which will increase the propelling power to such an extent that a ship equipped with the invention will have increased speed, but if not utilized 35 for increasing the speed then there will be a considerable saving in fuel.

With these and other ends in view, this invention consists in the details of construction and combination of elements hereinafter set forth and then specifically designated by the 40 claims.

In order that those skilled in the art to which this invention appertains may understand how to make and use the same, I will 45 describe its construction in detail, referring

50 by numerals to the accompanying drawings forming a part of this application, in which:

Fig. 1 is a conventional side elevation of 55 the stern of a ship or boat showing my invention applied thereto with parts broken away and shown in section to illustrate details of construction.

Fig. 2 is an enlarged face view of the train 60 of gears used for transmitting power from the secondary to the primary propeller.

In carrying out my invention as herein embodied, 5 represents a ship herein illustrated as a boat which travels in or on the water and in which the prime mover (not shown) is installed for revolving the shaft 6 65 on which is mounted a primary propeller 7. In building a new ship which is to embody my invention, this shaft may be of sufficient length to extend well to the stern of the propeller 7 but where the invention is to be applied to an old ship or one constructed along the lines of an old ship, then an auxiliary shaft 8 is provided which is connected to the stern end of the shaft 6 in endwise alignment 70 by means of a suitable coupling 9. The coupling illustrated is produced from companion flanges fixed to the meeting ends of the shaft 6 and its extension or auxiliary shaft 8 and the two flanges bolted together.

The stern end of the shaft, whether in one 75 piece or produced from the original shaft and an extension or auxiliary, is journaled in a suitable upright 10 located between and fixed to the overhanging stern of the ship body or hull and a keel extension 11. Any 80 usual rudder 12 may be provided and located to the stern of the upright 10.

85 A frusto-conical hub or shell 14 is mounted upon or surrounds a portion of the shaft to the stern of the primary propeller 7 with the smaller end of said hub or shell projecting 90 forwardly and journaled upon the shaft while the larger or stern end or base of said hub or shell is fixed to the ends of a cross 95 piece or bar 15 which is journaled upon the shaft to permit rotation of the hub or shell relative to said shaft or vice versa. Any 100 number of helixes 16 are carried by the hub or shell 14 and with the latter form a secondary propeller so curved that when revolving

in the ordinary manner that the ship is proceeding, it will have a forwardly boring action.

To the stern of the secondary propeller and in fact to the stern of the cross piece or bar 15 in spaced relation thereto and fixed to the shaft is a spur gear 17 meshing with a pair of pinions 18 which are located across the gear 17 at diametrically opposite points and journalled on axles 19, the ends of which are mounted in the circular plates or discs 20, one of which is located on each or toward each face of the gear 17 and in order to add rigidity to the parts and cause said circular plates or discs to revolve with the secondary propeller they may be attached to the cross piece or bar by means of the axles 19 or otherwise.

Located between the circular plates or discs 20 and surrounding the aforementioned gears so as to mesh with the pinions 18 is an internal ring gear 21 which is secured by a bolt 22 or other suitable fastening means to a bracket 23 which in turn is fixed to some part of the ship for instance to the keel extension 11. This internal ring gear is further braced to prevent rotation and maintain its setting with relation to the gear 17 and pinion 18 by a cap 24 which fits over the circular plates or discs 20 and is joined in a water tight manner with the larger end of the hub or shell 14 and said cap and internal ring gear are secured together by fastening means 25, such as screws, passing through the flange of the cap and threaded into the gear.

The cap 24 is fashioned so as to fit over the propeller shaft and the bracket 23 and is rigidly held in place by any desirable number of bolts or equivalent fastening devices 26 passing through the upright 10 and having threaded connection with the end wall of said cap.

In order to lubricate the gearing, a tube 27 may be provided and may run from the inside of the stern of the ship or from any other locality to the chamber within the hub 14 and its cap 24 or to the side of the train of gears through the cap. By making oil tight joints between the circular plates or discs 20 and the cap 24, the space between said circular plates or discs may be utilized as a lubricant chamber so that the gears can be submerged in a suitable lubricant if necessary.

The operation is as follows: The prime mover within the ship transmitting power to the propeller shaft will cause the primary propeller 7 to revolve. The revolution of the primary propeller will produce swirling revolving water currents and it might be said that these are discharged by the primary propeller. Such currents impinging against the helixes or convolute blades 16 of the secondary propeller will cause the latter to revolve and compel the pinions 18 which are connected with the secondary pro-

peller to walk around the internal ring gear 21 which is stationary and thus transmit power to the spur 17 so that the latter will revolve in the same direction as the propeller shaft and being fixed to said propeller shaft will assist in revolving the latter thereby adding a certain amount of power to the propeller shaft which may be utilized to increase the number of revolutions of the primary propeller 7 or to assist the prime mover in revolving the primary propeller at the predetermined rate of speed whereby less power is actually required from the prime mover and therefore a saving in fuel is obtained.

My experiments with this propeller have been carried on in motor boat L 5014 and the ratio and arrangements of the parts were such that the primary propeller made 100 R. P. M., while the secondary propeller made 40 R. P. M. The secondary propeller gradually increased the speed of the primary propeller to 130 R. P. M. without any additional power on the prime mover and under generally the same conditions at which the primary propeller would only make 100 R. P. M. under the most favorable conditions. Thus it is obvious with the same amount of fuel used in the prime mover, a greater amount of power is applied to the propeller shaft so as to increase the speed of the ship or at a predetermined speed the amount of fuel necessary to operate the prime mover may be considerably reduced.

Of course I do not wish to be limited to the exact details of construction herein shown and described as these may be varied within the limits of the appended claims without departing from the spirit of my invention.

Having thus fully described my invention, what I claim as new and useful is:

1. In a device of the character described, a propeller shaft including an extension rigidly connected therewith in endwise alignment, an upright to support the stern end of the extension, a secondary propeller journalled upon the shaft extension, a spur gear fixed to the shaft extension, a pair of discs one on each side of the spur gear, axles mounted in said discs, pinions journalled on said axles and meshing with the spur gear, said pinions, axles and discs being supported by and revolving with the secondary propeller, an internal ring gear enclosing and meshing the pinions and means to assist in maintaining the ring gear stationary and holding the same rigidly in place including a cap partially enclosing the discs and gearing and coacting with the secondary propeller, fastening means to connect said cap with the ring gear and other fastening means connected with the upright and said cap.

2. The structure set forth in claim 1, wherein the secondary propeller comprises a tapered hub with the smaller end contiguous

the primary propeller and helix blades on said hub.

3. The combination of a ship, a propeller shaft revolved by a prime mover, a primary propeller fixed to said shaft, a secondary propeller journalled on said shaft to the stern of the primary propeller and including a frusto-conical hub, the smaller end of which is contiguous the primary propeller, helix blades on said hub and a bar projecting across the larger end of the hub and journalled on the propeller shaft, a spur gear fixed on said propeller shaft to the stern of the secondary propeller, a plate on each side of said spur gear, axles fixed to said plates and said plate assembly being fixed to the bar on the secondary propeller, pinions journalled on said axles and meshing with the spur gear, an internal ring gear enclosing the pinions and meshing therewith, a keel extension, a bracket fixed to said keel and the ring gear to assist in holding said ring gear stationary, an upright between the overhanging stern of the ship and the keel extension and acting as a bearing for the outer end of the propeller shaft, a cap projected over the plate and gear assembly and providing a water tight joint with the hub of the secondary propeller, means to connect said cap and ring gear, means co-acting with said cap and the upright to hold said cap stationary and rigid and means to lubricate the gear assembly.

In testimony whereof, I have hereunto affixed my signature.

PAUL AUGNER.
